UNITED STATES PATENT OFFICE.

HENRY HILL, OF BROCKTON, MASSACHUSETTS.

SUPPORT FOR POLISHING SHOES.

Application filed November 22, 1926. Serial No. 149,907.

This invention relates to a support for holding shoes to be polished and has for its principal object the provision of a device for firmly holding a shoe at a desired height and 5 in convenient position so that the shoe may be thoroughly cleaned and polished without changing its position until the polishing operation is completed. Further objects of the invention reside in the particular details of 10 constructions hereinafter described and pointed out in the appended claims.

A preferred embodiment of the invention is illustrated in the accompanying drawings, in which:

15 Fig. 1 is a side elevation of the improved device showing a shoe in position; Fig. 2 is a horizontal section on the line 2—2 of Fig. 1; Fig. 3 is a detail section on the line 3—3 of Fig. 1, and Fig. 4 is a plan view of a lever 20 used in operating the device.

The support is adapted to be mounted upon a wall bench or table in a fixture 4, fastened at the desired height. The fixture is slotted to receive the outwardly tapered end 5 of a 25 horizontal bracket 6 which projects outwardly, substantially at right angles to the wall. A heel plate 7 and a toe plate 8 are carried on top of the bracket, the heel plate having a depending pin 9 and the toe plate a similar 30 pin 10, both passing through and slideable longitudinally of an elongate slot 11 in the bracket, guide studs 12 and 13 are also carried by the heel, and toe plates respectively, the studs extending into said slot to prevent rotational movement of the plates. The position 35 of the plates may be temporarily fixed by nuts 14 and 15 threaded upon pins 9 and 10 respectively, and bearing against the bottom surface of the bracket. The plates 7 and 8 have upstanding side flanges 16 and 17 respectively and the heel plate has a front flange 18, bearing against the sides of the heel and sole and the front of the heel, respectively, of a shoe resting upon the plates.

40 The position of the plates being adjustable as aforesaid, any size of shoe may be accurately fitted thereto.

Erected over the bracket and having its 45 lower end fixed in the bracket adjacent the wall fixture 4, is an angular frame 19 having a U-shaped flange 20 fixed at its outer end. The upper and lower arms of the flange have aligned apertures to receive a vertical rod 21 which extends therethrough toward the 50 bracket. A collar 22 carrying a set screw 23 is preferably fixed to the upper arm of flange

20, the set screw serving to fix the position of the rod 21, which is corrugated circumferentially between the upper and lower arms of the flange. The corrugations or pawls 24 60 are tapered downwardly and have flat radial top faces whereby the rod may readily be forced downwardly through the aperture in the lower arm, which has a diameter only slightly larger than that of the rod 21. The 65 aperture 25 in the upper arm (Fig. 3) may be greater in one dimension than the diameter of the rod to permit the rod to be tilted slightly if desired.

A knob 26 may be provided at the top of 70 the rod to permit the rod to be forced downwardly, as will be explained, but if greater leverage is desired the means hereinafter described are preferably employed. For this purpose spaced apart studs 29 and 30 are 75 fixed to the flanged member 20 and project toward the rod 21. The lower faces of said flanges are substantially flat and horizontal, as shown in Fig. 1.

When the apparatus is to be used, a shoe 80 is placed in position upon the adjusted heel and toe plates and the lock nuts 14 and 15 are tightened. A spring plate 27 which preferably carries a skeleton form 28 to support the top portion of the shoe adjacent the toe, 85 is placed in the shoe. The respective ends of the spring plate rests at the heel and toe of the shoe while the intermediate portion is arched considerably.

The rod 21 is pushed downwardly until its 90 lower end meets the arch of the spring plate 27, and is then forcibly pressed against the resistance of the spring, preferably by means of a bifurcated lever 31 which straddles the corrugated portion of rod 21, bears upon the 95 upper face of one of the corrugations and is fulcrumed at its inner end between the bosses 29 and 30. Pressure upon the lever is continued until the plate is flattened appreciably. The upper end of rod 21 may be slightly tilted 100 by hand to insure the engagement of the flat face of one of the corrugations with the lower arm of the flange member 20. The shoe is thus securely fixed upon the support and after the rod is additionally locked by tightening set screw 23, movement of the shoe by accident or intention is effectively prevented.

In such position all portions of the shoe 105 are readily accessible for cleaning and polishing purposes and these operations may 110 conveniently be performed by the workman when standing erect. The form 28 prevents

the collapse of the shoe under pressure and thus permits the shoe to be shined as satisfactorily as if the wearer's foot were inserted therein. The entire device may easily be removed from the wall, fixed and stored away when not in use, and when again erected may be adjusted and clamped with great rapidity.

Although the subject matter of this invention has been described in detail herein, it 10 will be apparent that various changes may be made in structural details without departing from the spirit of the invention as defined in the following claims.

I claim:

15 1. A support for shoes to be polished comprising a bracket having rests for the heel and toe of a shoe, a spring plate adapted to fit within the shoe and bear upon the insole thereof, a plunger movable downwardly into 20 contact with said plate and upwardly out of the shoe, so that the shoe may readily be placed upon and removed from the rests when the plunger is lifted, and means for forcing the plunger downwardly to depress the 25 spring plate and thereby to hold the shoe in fixed position upon said rests.

2. A support for shoes to be polished comprising an elevated bracket, having a heel and toe rest for a shoe, a spring plate adapted 20 to fit within the shoe and bear upon the insole thereof, a plunger movable into contact with said plate to depress the same, and means for locking the plunger upon the depressed 25 spring plate, whereby the shoe is held in fixed position.

3. A support for shoes to be polished comprising an elevated bracket having heel and toe rests for a shoe, a spring plate adapted to fit within the shoe and bear upon the bottom thereof, a frame extending over said bracket, and a rod movable downwardly in said frame to contact with said spring plate and depress the same, said rod having pawls engageable with a portion of said frame when 45 the rod is forced downwardly to depress the plate, whereby the rod is locked firmly to hold the shoe upon said rests.

4. A support for shoes to be polished comprising an elevated bracket having heel and toe rests for a shoe, a spring plate adapted to fit within the shoe and bear upon the bottom thereof, a frame extending over said shoe, a rod slideable through said frame at substantially right angles to said bracket, downward movement of the rod causing the bottom thereof to contact with and depress the spring plate, said rod having pawls engageable with a portion of said frame where the rod is forced downwardly to depress the plate,

whereby the shoe is firmly held upon said rests.

5. A support for shoes to be polished comprising an elevated bracket having heel and toe rests for a shoe, a spring plate adapted to fit within the shoe and bear upon the bottom thereof, a frame joined to said bracket and extending over said shoe, a rod slideable through said frame at substantially right angles to said bracket, downward movement of the rod causing the bottom thereof to contact with and depress the spring plate, said rod having pawls engageable with a portion of said frame where the rod is forced downwardly to depress the plate and supplemented locking means for retaining said rod in downward position whereby the shoe is firmly held upon said rests.

6. A support for shoes to be polished comprising an elevated bracket, a heel plate and a toe plate slideable longitudinally of the bracket, means for fixing the position of said plates with respect to the size of a shoe placed thereon, means for preventing rotational movement of said plates, a spring plate adapted to fit within the shoe and bear upon the bottom thereof, a frame extending over said shoe, and a rod slideable in said frame in a direction substantially at right angles to said shoe placed on said plates, downward movement of the rod causing the bottom thereof to contact with and depress the spring plate, and means for locking the rod to retain the plate in depressed position, whereby the shoe is firmly held upon said plates.

7. A support for shoes to be polished comprising an elevated bracket, a heel plate and a toe plate slideable longitudinally of said bracket, means for fixing the position of the plates with respect to the size of a shoe placed thereon, means for preventing rotational movement of said plates, upstanding flanges at the sides of the respective plates to restrain lateral movement of the shoe and a flange at the front of the heel plate to prevent forward movement thereof, a spring plate adapted to fit within the shoe and bear upon the bottom thereof, said plate having a form for supporting the top of the shoe, a frame extending over said shoe, and a rod slideable in frame in a direction substantially at right angles to said bracket, downward movement of the rod causes the end thereof to contact with and depress the spring plate, and means for locking the rod to retain the plate in depressed position, whereby the shoe is firmly held upon said plates.

In testimony whereof I affix my signature.
HENRY HILL
